Primary Examiner — Mary Ann Calabrese(74) *Attorney, Agent, or Firm* — Harness, Dickey & Pierce, P.L.C.**CLAIM**

The ornamental design for a stand-alone merchandising display, as shown and described.

DESCRIPTION

FIG. 1 is a front perspective view of a stand-alone merchandising display in accordance with my design;

FIG. 2 is a side view thereof, the side opposite to that shown is understood to be a mirror image thereof;

FIG. 3 is a front view thereof, it being understood that a rear view is a mirror image thereof; and,

FIG. 4 is a top view thereof.

In the drawings, the broken lines represent features that form no part of the claimed design.
